UNITED STATES PATENT OFFICE

GRIFFITH M. LEWIS, OF WATERVLIET, NEW YORK, ASSIGNOR TO WILLCOX & GIBBS
SEWING MACHINE CO., OF NEW YORK, N. Y., A CORPORATION OF NEW YORK

SEWING MACHINE

Application filed May 26, 1927. Serial No. 194,387.

This invention relates to improvements in sewing machines, and more particularly has as its object the provision of means, designed especially for feed-off-the-arm felling sewing machines, for mounting the felling folder of the machine in front of the presser foot in a manner to enable said folder to be readily shifted—during any operation or part of an operation when it is desirable or necessary to put the folder out of action—from its operative or active position to an out-of-the-way inoperative or inactive position in which it will not obstruct or otherwise interfere with the feeding of the work, or with manipulation and handling of the work and its ready and proper presentation under the presser foot and to the needles.

5 The aforesaid and other objects and advantages are attained by what is now believed to be the preferred embodiment of the invention illustrated in the accompanying drawing, wherein.

10 Fig. 1, is a perspective view of a sewing machine having a folder mounted on the work arm thereof in accordance with the present invention;

15 Fig. 2, is a perspective view of the cuff end of a sleeve partly closed by a seam such as made on the machine of Fig. 1;

20 Fig. 3, is a top plan view of the cover plate of the work arm of the machine and showing also the folder and part of the presser foot; and

25 Fig. 4, is a longitudinal section through part of said cover plate.

30 In the drawing, the folder and means for mounting the same are shown in conjunction with the commercially well known "Feldlock machine" of the Willcox & Gibbs Sewing Machine Company. The hollow machine frame or casing, shown in Fig. 1, includes hollow standards 20 and 21 at opposite ends of said frame, connected by a hollow bridge portion 22. The feed-off-the-arm hollow work arm of the machine includes an upper part 23 extending horizontally outward from and forward as a continuation of the upper end of the hollow standard 21; a vertically depending part 24 (only a fragment of which appears in Fig.

35 1); and a horizontal work-supporting part 25 having a free end off which the work is fed. At its upper end the hollow standard 20 extends forward and constitutes the head 26 of the machine which partly overhangs the end of the horizontal work-support 25 of the work-arm. At the free end of said part 25 of the work-arm there is a throat plate or cloth plate 27 having therein suitable slots in and through which operate rows of teeth of a feed dog (not shown), the rear ends only of said slots showing beyond the rear end of the presser foot in Fig. 1. Such feeding mechanism operates to feed the fabric or work along the part 25 of the work arm and toward and off the free end thereof where it passes over the throat plate 27 and under the presser foot.

40 55 60 65 70 75 80 85 90 95 100

30 is a hinged presser foot fulcrumed by a screw pivot 31 to the foot shank 32 which is securely clamped to the lower end of a presser foot bar 33. The needles 34, 34, clamped to the lower end of needle bar 35, operate through their respective needle openings in the presser foot and cloth plate 75 and cooperate with suitable looper mechanism (not shown) operating in the free end of the work arm beneath the cloth plate 27. Any desired or suitable number of needles may be used.

35 A removable cover plate 40 for the part 25 of the work arm has at one end a beveled lip 41 adapted to engage in a correspondingly undercut recess in one end of the cloth plate 27, and at its other end said cover is secured in place by a spring-actuated bolt latch 42 having a conical point adapted to seat in a conical depression in a fixed part of the wall of the work arm, as best shown in Fig. 3. By an upward pull or lift on this cover plate 40 at its forward end where the latch bolt 42 is located, said bolt will be readily disengaged from its seat and the cover plate thus released for removal by disengagement of the lip 41 from the undercut recess in the edge of the throat plate.

40 45 50 55 60 65 70 75 80 85 90 95 100

The parts as thus far described in the detailed description are substantially the same as in the aforesaid commercial Feldlock machine.

The arm cover-plate 40 is formed with a flattened upper surface portion 50, Fig. 4, upon which a U-shaped plate 51 is fastened by screws 52. A slide plate 53 fits and slides between the two arms of plate 51, beveled edges of said plate engaging beneath undercut inner edges of the two arms of plate 51. The folder is secured to the slide plate 53 in the manner presently described, whereby 10 said plate constitutes a carrier for said folder movable or slideable longitudinally of the work arm. A spring plate 54, fastened to slide plate 53, has a rounded pointed detent pin 55 adapted to engage one or the other 15 of two depressions or seats 56, 57 in the flat surface 50, thus to hold the slide plate positively either in its advanced position, when pin 55 engages seat 56, or in its retracted position when pin 55 engages seat 57.

20 60 is a folder of a well known commercial type, having a slot 61 in the base plate thereof, through which slot a screw 62 passes to fasten the folder to the slide plate 53 with a limited range of adjustment permitted by 25 said slot.

The folder 60 is shown in its forward active or operative position in Figs. 1, 3 and 4, with its delivery end close to the forward end of the presser foot and the detent pin 30 55 of the slide plate 53 in engagement with slot 56. But there are frequent occasions when it is desirable to operate the machine without using the folder during a portion of an operation, but with the folder shifted to 35 an inactive out-of-the-way position removed from the presser foot, but from which position it may be moved back into active position for continuance of the operation.

For example, Fig. 2, illustrates the starting 40 of a seam for closing the sleeve of a garment, such as an overall one-piece suit, or jacket, having a double thick hemmed cuff. Across the cuff the stitches must pass 45 through eight thicknesses of fabric interfolded into felled relationship. Hence for this short length there are too many thicknesses of fabric to be passed through a folder adapted to operate efficiently with half as 50 many thicknesses in the main lengths of the seams. Therefore, the folder 60 is withdrawn or shifted to an inactive position by 55 sliding the plate 53 to the right until its detent pin 55 engages seat 57. The operator then has space and clearance between the 60 delivery end of the folder and presser foot in which to arrange and manipulate the fabric clear of the folder to begin and complete that portion of the seam across the cuff, whereupon, and without stopping the machine, she may slide the folder forward to 65 its active position in a manner to cause it automatically to engage properly the two edges of fabric which it will thereafter interfold in felled relationship in continuing the seam. In repairing defective places in

felled seams it is also highly advantageous to be able to move the folder from one of its said positions to the other.

What is claimed as new is:

1. In a sewing machine, the combination 70 of stitch forming elements; a presser foot; a work-arm having an approximately horizontal work-supporting part; work feeding means for feeding work along said work-supporting part of the arm past the presser foot and stitch forming elements; and a folder 75 movably mounted on said work supporting part of the arm in front of the presser foot to move approximately longitudinally of said part of the arm from an active position close to the presser foot to an inactive position removed therefrom.

2. In a sewing machine, the combination 80 of stitch-forming elements; a presser foot; a work-arm having an approximately horizontal work-supporting part free at one end 85 at which said stitch-forming elements and presser foot operate; work-feeding means for feeding work along said work-supporting part of the arm past the presser foot 90 and stitch forming elements and off the free end of said part of the arm; and a folder 95 movably mounted on said work supporting part of the arm in front of the presser foot to move approximately longitudinally of said part of the arm from an active position close to the presser foot to an inactive position removed therefrom.

3. In a sewing machine, the combination 100 of stitch forming elements; a presser foot; a work-arm having an approximately horizontal work-supporting part free at one end; work-feeding means for feeding work along said work-supporting part of the arm past the presser foot and stitch forming elements; a detachable and removable plate along said work supporting part of the work arm in advance of the presser foot; and a folder 105 movably mounted on said plate to move approximately longitudinally of said part of the work arm from an active position close to the presser foot to an inactive position removed therefrom.

4. In a sewing machine, the combination 115 of stitch forming elements; a presser foot; a work arm having an approximately horizontal work-supporting part free at one end at which said stitch forming elements and presser foot operate; work feeding means for feeding work along said work-supporting part of the arm past the presser foot and stitch forming elements and off the free end of said part of the arm; a detachable and removable cover plate along said work 120 supporting part of the arm in advance of the presser foot; and a folder movably mounted on said cover plate to move approximately longitudinally of said part of the work arm 125 from an active position close to the presser 130

foot to an inactive position removed therefrom.

5. In a sewing machine, the combination of stitch forming elements; a presser foot;

5 a work-arm having an approximately horizontal work-supporting part free at one end

at which said stitch forming elements and presser foot operate; work-feeding means for feeding work along said work-support-

10 ing part of the arm past the presser foot and

stitch forming elements and off the free end of said part of the arm; a detachable and removable cover plate along said work sup-

15 porting part of the arm in advance of the presser foot; a slide plate slidably mounted

on said cover plate to move approximately longitudinally of said part of the work arm; and a folder mounted on said slide plate and

15 in front of the presser foot, whereby move-

20 ment of the slide plate in one direction pre-

sents the folder in active position to the presser foot and in the other direction moves the folder to an inactive position removed

from the presser foot.

25 6. In a sewing machine, the combination

of stitch forming elements; a presser foot;

a work-arm having an approximately horizontal work-supporting part free at one end at which said stitch forming elements and

30 presser foot operate; work-feeding means for feeding work along said work-support-

ing part of the arm past the presser foot and stitch forming elements and off the free end of said part of the arm; a detachable and re-

35 movable cover plate along said work sup-

porting part of the arm in advance of the presser foot; a slide plate slidably mounted

on said cover plate to move approximately longitudinally of said part of the work arm;

40 a folder mounted on said slide plate and in front of the presser foot, whereby movement

of the slide plate in one direction presents the folder in active position to the presser foot and in the other direction moves the

45 folder to an inactive position removed from the presser foot; and detent means for hold-

ing the slide plate in said active or inactive

position of the folder.

7. In a sewing machine, the combination

50 of stitch forming elements; a presser foot;

a work-arm having an approximately horizontal work-supporting part free at one end at which said stitch forming elements and

presser foot operate; work-feeding means

55 for feeding work along said work-support-

ing part of the arm past the presser foot and stitch forming elements and off the free end of said part of the arm; a plate slidably mounted on said work-supporting part of

60 the work arm in advance of the presser foot

to move approximately longitudinally of said part of the work arm; and a folder mounted on said slide plate and in front of

the presser foot, whereby movement of the

65 slide plate in one direction presents the

folder in active position to the presser foot and in the other direction moves the folder to an inactive position removed from the presser foot.

8. In a sewing machine, the combination

70

of stitch forming elements; a presser foot;

75

a work-arm having an approximately horizontal work-supporting part free at one end at which said stitch forming elements and

presser foot operate; work-feeding means

80

for feeding work along said work-support-

ing part of the arm past the presser foot and

stitch forming elements and off the free end of said part of the arm; a folder carrier mounted on said work-supporting part of

85

the arm in advance of the presser foot to move approximately longitudinally of said part of the work-arm; and a folder mounted

90

on said folder carrier and in front of the presser foot, whereby movement of the folder carrier in one direction presents the

95

folder in active position to the presser foot and in the other direction moves the folder to an inactive position removed from the

presser foot.

In testimony whereof I have signed this specification.
